VOLUME COMPRESSION DEVICE FOR
SOUND REPRODUCERSGlenn L. Dimmick, Haddonfield, N. J., assignor
to Radio Corporation of America, a corpora-
tion of Delaware

Application April 14, 1938, Serial No. 202,085

6 Claims. (Cl. 250—41.5)

This invention relates to volume compression devices and more particularly to a type of volume compression devices peculiarly adapted to use in photoelectric sound reproducers.

5 In some sound reproducing devices used in theatres, trouble has been heretofore encountered due to the reverberation characteristics of the theatres and this trouble has been particularly noticeable where variable area sound records, 10 which have a very wide range of both amplitude and frequency response, are used. The trouble is not so noticeable in variable density recording due to the limitations of the photographic material which tends to flatten out the response 15 in accordance with the shape of the H and D curve for the particular material used.

Such difficulties have sometimes been compensated for in specific theatres by the addition 20 of volume compressors in the thermionic amplifiers used which compress the volume by making the amplification an inverse function of the volume.

The present invention provides a very much simpler but nevertheless equally or more effective means for securing such volume compression and consists in the insertion of a very high resistance in the lead from the negative side of the polarizing supply for the photocell and between the said supply and the output 25 transformer.

One object of my invention is to provide an improved apparatus of and method for volume control.

Another object of my invention is to provide 30 an improved device for limiting the volume of output in a sound reproducer.

Another object of my invention is to provide an improved volume compressor.

Another object of my invention is to provide 35 an improved volume compressor adapted to operate directly in the photocell circuit.

Another object of my invention is to provide a volume compressor which requires no auxiliary tubes in the amplifier.

40 Other and incidental objects of my invention will be apparent to those skilled in the art from a reading of the following specification and an inspection of the accompanying drawing, in which

Figure 1 shows my invention as applied to a 45 push-pull photocell circuit,

Figure 2 is a graph of current sensitivity plotted against anode volts on two types of photocells,

Figure 3 is a curve showing resistance in 50 megohms of the resistor applied in accordance

with my invention plotted against volume compression in decibels, and,

Figure 4 is a schematic diagram of my invention as applied to a single photocell.

Referring first to Figure 1, a push-pull photocell 10 having cathodes 11 and 12 and a common anode circuit 13 is supplied with current from an appropriate source of supply 14, such as a B battery or an equivalent source of supply. The output from the photocell is passed through the primaries 15 and 16 of a push-pull transformer, from the secondary 11 of which current is led to an appropriate amplifier. In the performance of my invention, I insert a resistor 18 between the negative side of the source of current 14 and the transformer primaries 15 and 16, the positive side of the said source of current being connected as usual to the anode of the photocell.

A gas-type photocell is preferably used. 20

When the emission of the photocell cathodes 11 and 12 is modulated by means of a class A push-pull sound record, current flows through windings 15 and 16. The current through the two windings 15 and 16 including a direct current component which passes through the resistor 18 and audio frequency component which passes through the two windings but not through the resistor 18. The amount of direct current required by the photocell, however, varies in accordance with the amplitude of the audio frequency output. Since the resistor 18 does not affect the audio frequency currents passing through the windings 15 and 16, it may be made of any desired value without affecting the said 30 audio frequency current. 35

As shown in Figure 2, the sensitivity of the gas photocell increases very greatly with an increase in applied voltage. Since the resistor 18 is in series with the source of direct current supply to the photocell, when the photocell current increases, due to increased modulation, the voltage drop across the resistor 18 increases correspondingly and the applied voltage in the photocell 10 is at the same time decreased, since only a fixed 40 voltage is available from the source 14. This causes the sensitivity of the photocell 10 to fall off as the amplitude of the applied signal increases and the amount of this decrease in photocell sensitivity is shown in Fig. 3, where the 45 volume compression in decibels is plotted against the value of the resistance 18 in megohms. It will be apparent from Figure 3 that a resistance of 65 megohms, for example, will give a volume compression of 10 db. 50

The operation of this circuit is dependent upon the fact that, in class A sound records, ground noise reduction is customarily used and the total volume of light transmitted by the track varies directly with the amplitude of the signal. If the amount of light transmitted by the track is controlled in the manner described and claimed in my application Serial No. 168,173, filed October 9, 1937, (RCV D-5374), the noise reduction envelope may be made to anticipate the signal and this will cause the volume compression to anticipate the signal, decreasing the sensitivity of the photocell just an instant before the signal arrives.

If it is desired to apply this system of volume compression to a single photocell, this may be accomplished as shown in Figure 4. In this circuit, the photocell 20 is connected to the source of current 14 in the same manner as described for Figure 1 and the output of the circuit is connected to an appropriate transformer 21. This circuit differs, however, from that of Figure 1 in that there would be a tendency for the direct current to pass through the primary of the transformer 21 and a blocking condenser 22 is accordingly inserted in series with this primary, while the primary is shunted by means of the resistor 23 which serves to carry the direct current. The resistor 18 is also shunted by a bypass condenser 24 so that the said resistor need not carry any audio frequency current. The circuit otherwise operates in the same manner as the circuit shown in Figure 1 and described above.

In this latter system, the volume compression, like that in the system shown in Figure 1, depends upon the use of ground noise reduction sound records, where the total volume of light passing through the sound record varies in proportion to the amplitude of the signals to be reproduced.

Having now described my invention, I claim:

1. Apparatus of the class described including a push-pull photocell, a push-pull output circuit, power supply means connected from an electrode of said cell to the midpoint of said output circuit, and a resistance of not less than 20 megohms between said power supply means and said midpoint.

2. Apparatus of the class described including a push-pull photocell, a push-pull output circuit, power supply means connected from one electrode side of said cell to the midpoint of said output circuit, and a resistance of not less than 20 megohms between said power supply means and said midpoint.

3. Photoelectric apparatus including a light translating means having an anode and a cathode, power supply means connected to the anode of said light translating means, an output coupling device connected to the cathode of said means, and resistance of not less than 20 megohms between said power supply and said output coupling device.

4. Photoelectric apparatus including a light translating means having an anode and a cathode, power supply means connected to one electrode side of said light translating means, an output coupling device connected to the other electrode side of said means, and resistance of not less than 20 megohms between said power supply and said output coupling device for producing volume compression.

5. In combination, a photocell, an output transformer, a power supply connected to the anode of said photocell, the cathode of said photocell being connected to said transformer and a resistance of not less than 20 megohms connecting the negative terminal of said power supply and said output transformer.

6. In combination, a photocell, an output transformer, a power supply connected to one electrode side of said photocell, the other electrode side of said photocell being connected to said transformer and a resistance of not less than 20 megohms connecting the negative terminal of said power supply and said output transformer.

GLENN L. DIMMICK.
